Inventor

James A. Mc Kelvy
By Frank S. Averman.

Attorney

UNITED STATES PATENT OFFICE.

JAMES A. MCKELVY, OF HARRISBURG, PENNSYLVANIA.

TRAFFIC SHELTER.

Application filed April 15, 1922. Serial No. 553,255.

To all whom it may concern:

Be it known that I, JAMES A. MCKELVY, a citizen of the United States of America, and resident of Harrisburg, in the county of 5 Dauphin and State of Pennsylvania, have invented certain new and useful Improvements in Traffic Shelters, of which the following is a specification.

This invention relates to shelters that are 10 particularly adapted for use by policemen or traffic officers as a protection from the elements, the said invention having for an object the provision of a novel shelter or tent-like structure which may be portable and 15 collapsible; the said device being effective to protect the occupant from rain and wind, while at the same time enabling the occupant to manipulate or operate a semaphore or signal by which the traffic is directed.

20 It is a further object of this invention to produce a shelter of the character indicated, with a platform and suitable shields or walls, preferably having transparent panes, in order that the observation may be in all 25 directions from within the shelter.

It is a further object of this invention to produce a shelter of the character indicated which will withstand the force of wind without becoming distorted or displaced, so that 30 practically regardless of weather conditions, the occupant of the shelter will be comparatively comfortable.

With the foregoing and other objects in view, the invention consists in the details of 35 construction, and in the arrangement and combination of parts to be hereinafter more fully set forth and claimed.

In describing the invention in detail, reference will be had to the accompanying 40 drawings forming part of this application, wherein like characters denote corresponding parts in the several views, and in which—

Figure 1 illustrates a view in side elevation of the shelter and signaling device;

Figure 2 illustrates a front view of the shelter;

Figure 3 illustrates a top plan view thereof;

50 Figure 4 illustrates a plan view of the floor;

Figure 5 illustrates an enlarged sectional view of a fragment of the shelter;

Figure 6 illustrates a plan view of the roof frame;

Figure 7 illustrates a sectional view thereof; and

Figure 8 illustrates a sectional view through the posts, showing the floor board in plan.

In these drawings 10 denotes the base which may be a box-like structure of any suitable type, through the approximate center of which a pivot bolt 11 extends, the said bolt also projecting through the floor frame 65 12 on which the floor board 13 is supported, it being the purpose of the inventor that the floor frame shall be capable of rotation on the base, in order that the open portion of the shelter shall be faced in different directions.

The floor board may have a plurality of studs 14 in its edge, to which the shelter wall 15 is secured by temporary fastenings such as snap fastenings and the like, so that the 75 shelter wall may be applied to or removed from the floor board. The shelter wall, in the present embodiment of the invention, comprises preferably a canvas or like fabric having a plurality of openings such as 16. 80 protected by transparent panes 17 of material such as celluloid, and the shelter wall may have apertures such as 18 covered with aprons 19 that are free from the shelter wall, except along their top edges in order that the 85 hand of the operator may be extended through the openings in the shelter wall for the purpose of gaining access to the semaphore operating mechanism.

The floor board is provided with a plurality of base sockets 20 in which posts 21 are fitted, and these posts preferably have reduced upper ends 22 that enter apertures 23 in the roof frame 24, it being shown that the roof frame, in the present embodiment of the 95 invention, comprises a substantially circular marginal band 24^a and cross ribs 25 with their ends anchored to the band. The cross ribs are preferably arched so that the covering of the shelter will shed water expeditiously.

The shelter wall may be extended over

the roof frame and it may be secured thereto by appropriate fastenings 26, according to the requirements in practice. The marginal band has a depending flange 27 forming an anchorage for the fastenings 26.

The inner surfaces of the shelter wall have guides or rings 28 which embrace the posts and retain the parts in proper positions, preventing undue flapping of the shelter wall which might result through the wind pressure. The guides are preferably made of strips of canvas having ordinary snap fasteners.

A rod 29 extends across the open front of the shelter wall and it has eyes 30 which are slidable on two of the posts 21, the said rod being held at different positions of adjustment by set screws 31. A foot covering or apron 32 is connected to the said rod, and it may be adjusted in height as the rod is moved. The lower end of the foot covering or apron may be secured to the edge of the platform in appropriate way, and when these parts are properly adjusted, rain will be prevented from gaining access to the feet of the occupant of the shelter, and the feet of the occupant will likewise be protected from the wind.

The semaphore or signal 33 may be of any appropriate type, and as the construction of the semaphore is immaterial, the parts thereof will not be described, except as to the provision of anchorages 34 such as pins or the like, for the hooks 35 by which the semaphore is connected to the frame of the shelter at the top, and the anchorage 36 on the base of the semaphore for engaging the hooks 37 extending from the base of the shelter.

From an inspection of the drawing, and from the foregoing description, it will be seen that the shelter may be constructed to withstand unusual exposure, and that the occupant of the shelter will be protected to a very great extent by reason of the fact that the shelter wall can be almost wholly closed and yet the occupant may observe traffic and operate the semaphore to direct it.

Furthermore, the parts of the shelter may be dismantled and stored in comparatively small space, whereas it can be readily set up for use by people of ordinary skill.

I claim:

1. In a shelter, a floor, a shelter wall secured at its lower end to the floor, a roof frame, posts anchored on the floor and connected to the frame to support the frame, the shelter wall having transparent sections and covered openings, means for securing the said shelter wall to the roof frame, a cover for the roof frame, rings connected to the shelter wall through which the posts extend, a rod having eyes slideable on two of the posts, a foot covering connected to the rod, and means for holding the rod at different positions of adjustment.

2. In a shelter, a base, a bolt therethrough, a floor frame through which the bolt extends, a floor on the said frame, a shelter wall having its lower end connected to the edge of the floor, a roof frame, posts for supporting the roof frame, post sockets on the floor in which the said posts are anchored, means for connecting the said posts to the roof frame, means for securing the shelter wall to the roof frame, a cover for the roof frame, a foot covering at the front of the shelter wall, and means for suspending the foot covering.

3. In a shelter, a base, a bolt therethrough, a floor frame through which the bolt extends, a floor on the said frame, a shelter wall having its lower end connected to the edge of the floor, a roof frame, posts for supporting the roof frame, post sockets on the floor in which the said posts are anchored, means for connecting the said posts to the roof frame, means for securing the shelter wall to the roof frame, a cover for the roof frame, a foot covering at the front of the shelter wall, means for supporting the foot covering comprising a rod having eyes slideable on two of the posts, and means for securing the rod at different positions of adjustment.

JAMES A. MCKELVY.
